UNITED STATES PATENT OFFICE.

JUSTUS A. TRAUT AND CHRISTIAN BODMER, OF NEW BRITAIN, CONNECTICUT; SAID BODMER ASSIGNOR TO SAID TRAUT.

PLANE.

SPECIFICATION forming part of Letters Patent No. 515,063, dated February 20, 1894.

Application filed August 9, 1893. Serial No. 482,771. (No model.)

To all whom it may concern:

Be it known that we, JUSTUS A. TRAUT and CHRISTIAN BODMER, citizens of the United States, residing at New Britain, in the county 5 of Hartford and State of Connecticut, have invented certain new and useful Improvements in Planes, of which the following is a specification.

This invention relates to adjustable-mouth 10 planes, the object being to furnish means for adjusting the mouth-slide and for holding the same in place.

In the drawings accompanying and forming a part of this specification, Figure 1 is a 15 plan view of a portion of a plane furnished with our present improvements. Fig. 2 is a sectional side view of the plane. Figs. 3 and 4 are views similar to Figs. 1 and 2, respectively, for illustrating the mode of operation 20 of the improvement. Fig. 5 is a view similar to Fig. 1, showing a modification of the improvement. Fig. 6 is a sectional side view of a portion of the same. Fig. 7 is a view similar to Fig. 1, showing another modification.

25 Similar characters designate like parts in all the figures.

Referring to Figs. 1, 2, 3 and 4, the letter B designates the forward portion of an ordinary iron smoothing-plane of the class which 30 are usually provided with a mouth-slide, also sometimes designated as an "adjustable front," for regulating the width of the mouth 2, of the plane. The usual plane-iron or cutter is shown in place at 3, held under the forward end of the ordinary clamp, 4, in a well-known manner.

The mouth-slide designated by 5, is shown provided with a stud, 6, preferably rigidly fixed therein as indicated in Figs. 2 and 4. 40 Said stud 6 extends upward through the forward end, 7, of the plane-frame, and is provided on its threaded upper end with a clamping nut, 8, whereby to hold the mouth-slide in place.

45 According to our present improvements, the plane is furnished with a mouth-slide actuator, designated in a general way by D, and whose principal portion constitutes an adjustable block or thrust member, designated 50 by 9, intermediate to some part of the mouth-

slide and a suitable fixed stop-abutment, as, for instance, the pin 10, on the plane-frame. In the preferred form thereof shown in Figs. 1 to 4 inclusive, said actuator consists, essentially, of an eccentric disk 9; this is shown 55 provided with a loop or outer bar, 11, bearing against the opposite side of the aforesaid abutment-pin 10, as clearly shown in said figures. By turning the actuator D toward the right-hand or left-hand, as for instance from 60 the position shown in Figs. 1 and 2 to that shown in Figs. 3 and 4, the mouth-slide will be moved, in the present instance toward the right-hand for widening the open space, 2', between said slide and the cutter 3, as will 65 be seen by comparison of said figures of the drawings. The actuator D, being set on the plane-frame underneath the clamp-nut 8, is thereby rigidly held in place when said nut is screwed down for holding the mouth-slide. 70

The actuator D is shown pivotally supported on the stud 6 of the mouth-slide 5, so that in connection with the actuator slot 12, and the abutment-pin 10, said actuator holds the mouth-slide positively against movement 75 in either direction; said abutment-pin fitting closely but freely within said slot, and the forward and rearward sides of said pin constituting oppositely-disposed stop-abutments.

In Figs. 5 and 6 we have shown a modification of the invention, in which the actuator, here designated by D', consists of an eccentric disk 9', which fits on the clamp-screw 8', and works between the forward and rearward abutments 14 and 15, of the plane-frame 85 (see Fig. 6) so as to control the position of the mouth-slide in substantially the same manner as described in connection with Figs. 1 to 4 inclusive. Said disk 9' is shown furnished with a knurled rim 16, whereby the 90 operator may conveniently turn the actuator for adjusting the mouth-slide.

In Fig. 7 there is shown a further modification of the improvement, in which the actuator D'' consists of a flat lever 17, fitted over 95 the stud 6, (this being the same as the one shown in Figs. 1 to 4 inclusive) and having a pin or stud, 18, fitting in an eccentric groove, 19, between the forward and rearward abutments 20 and 21, formed on the plane-frame 100.

and corresponding to those shown in Figs. 5 and 6 and also (in reverse order) to the forward and rearward sides of the abutment-pin 10 shown in Figs. 1, 2, 3 and 4. In Fig. 7, the 5 clamp-nut is omitted for the purpose of more clearly illustrating the other features; but it is or may be the same as the one shown in Figs. 2 and 4. In Figs. 5 and 6, the clamp-screw 22 is shown formed integral with the 10 head 8', and in working engagement with the corresponding internal thread of the mouth-slide, as will be understood from Fig. 6.

Having thus described our invention, we claim—

- 15 1. In a plane, in combination, a plane frame having a stop-abutment upon the upper face thereof, a mouth-slide having a fixed stem, vertical thereto, an independently operable mouth-slide actuator supported upon the upper face of the plane-frame and engaging the
- 20

stem and stop-abutment so as to rotate about said stem and against said abutment, and means for clamping said actuator against the plane-frame, substantially as described.

2. In a plane, in combination, the plane-frame having an abutment or stop upon the upper face thereof, a mouth-slide, a stem fixed at one end to the mouth-slide and having a clamp-nut adjustably secured to its opposite end, an independently operable eccentric 30 loosely carried by the stem intermediate to the upper face of the frame and the clamp-nut and in engagement with the abutment, substantially as described and for the purpose set forth.

JUSTUS A. TRAUT.
CHRISTIAN BODMER.
